UNITED STATES PATENT OFFICE.

VICTOR NIVOIS, OF NEW YORK, N. Y.

DESIGN FOR A WATCH OR LOCKET CASE.

SPECIFICATION forming part of Design No. 16,972, dated November 2, 1886.

Application filed August 19, 1886. Serial No. 211,315. Term of patent 3½ years.

To all whom it may concern:

Be it known that I, VICTOR NIVOIS, of the city, county, and State of New York, have invented and produced a new and original Design for Watch and Locket Cases, of which the following is a specification.

The nature of my design is fully represented in the accompanying drawing, to which reference is made.

10 The design consists of the scalloped circular center *a* and the radiating diamond-shaped figures *b*, projecting from the outer edge of the circular center *a*. Between the diamond-shaped figures *b* appears a representation of 15 a branch, *c*, bearing leaves *c'*, a central flower, *c''*, and a cluster of leaves, *c'''*. The diamond-shaped figures *b* terminate in a rose, *b'*, and within each diamond-shaped figure appears a leaf, *b''*.

20 I claim—

1. The design for watch cases or lockets, the same consisting of a circular center, *a*, and radiating diamond-shaped figures *b*, terminating in a rose, *b'*, as shown.

2. The design for watch cases or lockets, 25 the same consisting of a circular center, *a*, the radiating diamond-shaped figures *b*, and the branches *c*, as shown.

3. The design for watch cases or lockets, 30 the same consisting of a scalloped circular center, *a*, radiating diamond-shaped figures *b*, branches *c*, the diamond-shaped figures terminating in a rose, *b'*, and showing a leaf, *b''*, the branches showing leaves *c'*, central flower, *c''*, and cluster *c'''*, as shown.

VICTOR NIVOIS.
